UNITED STATES PATENT OFFICE.

JOHN E. STRIETELMEIER, OF CINCINNATI, OHIO, ASSIGNOR TO THE IDEAL WHEEL COMPANY, OF CINCINNATI, OHIO, A CORPORATION OF OHIO.

SPRING-WHEEL.

1,348,834.

Specification of Letters Patent.

Patented Aug. 3, 1920.

Application filed November 3, 1913. Serial No. 798,905.

To all whom it may concern:

Be it known that I, JOHN E. STRIETELMEIER, a citizen of the United States, residing at Cincinnati, in the county of Hamilton 5 and State of Ohio, have invented certain new and useful Improvements in Spring-Wheels, of which the following is a specification.

This invention deals with a resilient wheel and it is exemplified in several of its embodiments by drawings in which Figures 1, 2, 3, 10 4 and 5, show a sectional side elevation, a radial section, and perspectives of a spoke element, a hub-wedge-block, and a hub-bolt-cover, respectively, all of one embodiment in 15 which sockets are swaged in the felly-band and the clamping member is devoid of side-flanges. Figs. 6 and 7 are circumferential and transverse sections of a modification having similar characteristics. Figs. 8, 8^a 20 and 9 show a flangeless clamping member and a socket-block secured to a rim element. Figs. 10, 11, 12 and 13 show a rim element recessed to receive a socket-block and illustrates the details of this construction which 25 proposes the use of a clamping member having flanged sides. Figs. 14, 15, 16 and 17 are views of a similar construction using flanged clamping members, but another type 30 of socket block. Figs. 18 and 19 are a side elevation, partly in section, and a radial section, respectively, of a portion of the wheel, on a larger scale.

The spokes of the wheel emerge from the hub in loop-like form, and each loop-like 35 spoke consists of two flat-metal spoke-elements 3, 3, which are curved as shown to augment their normal resiliency and which both converge toward the rim and are both secured thereto by a single fastening arrangement which in its relation to the spoke-elements 40 is more especially the subject of this application. The construction at the hub need not here be elaborated as it is described and claimed in my copending application, 45 No. 720,521, filed Sept. 16, 1912.

This invention proposes a rim construction providing an equispaced series of sockets of either the open-side type 11 or the closed-side type 11^a, and which are adapted snugly 50 to receive the flanged ends or feet 12 of the spoke elements, all in coacting relation with a clamping member, and a draw-up lever- 55 age device for adjustably forcing the clamp-

ing member into or toward said socket to clamp said spring-feet by pressure in the 55 same.

The inner ring or felly-band of the rim may be an annular U-shaped channel piece 10 in which the sockets 11^a are indented at 60 regular intervals in a radial direction, in this instance preserving the side-walls substantially in parallelism, but having the end walls 1 inclined at an angle to a radius to converge somewhat toward the bottom 2, so as to permit the spoke elements to enter the 65 sockets at an angle to the radius. This bottom 2 extends in a circumferential or tangential direction, and as shown by Figs. 1, 2, 6 and 7, the bottom 2 of the socket indented in the felly-band 10 receives support from 70 the felly proper (7) whereby it is braced against movement under the strains of the flexible spokes. This socket support may assume various forms. Thus, as indicated by Figs. 1 and 2, a filler-block 4 of wood or 75 metal may intervene between the bottom 2 of the socket and the adjacent face of the felly proper, or, as shown by Figs. 6 and 7, a counterpart pocket 9 may be formed in the felly-proper 7 and its bottom 5 may be in flat- 80 wise contact with the bottom 2 of the spoke-socket so as to support the same. These pockets 9 may be formed at the inner peripheral face of the felly proper and this inner 85 face or portion may extend in the form of a circumferential rib 6 of greater or lesser size or proportions, as indicated by Fig. 6. These pockets 9 may be very advantageously also utilized to contain the squared enlarged head of a bolt, as shown by Fig. 6, or these pockets 90 may be given the form of conical apertures 9^a shown by Fig. 1 and adapted to receive the conically upset ends of the bolts.

The spoke receiving sockets may also be provided by separate blocks secured to the 95 inner periphery of the rim. The socket-block may be simple U-shaped form as indicated by 15 in Fig. 16 having open sides and end walls 17 providing converging inner 100 spring-supporting faces 18 and mounted directly upon the rim-member and positioned as by pins 19. Or the socket-block may be of the straddle or saddle type shown by Fig. 13 or Fig. 10. In the case of the saddle-socket-block 20, the inner felly band 10^a may 105 be of wood suitably mortised at intervals to

receive the saddle block and bring the side flanges 21 thereof in flush relation with the wood. The modified type of straddle-socket-block 22 of Fig. 8^a is suitable for use 5 in connection with the felly-band 10^b having a semi-circular cross-section. The side flanges 23 of this block straddle said band 10^b without requiring any in-cutting thereof. Preferably the end walls 24 and 26 of these 10 blocks will provide inclined inner faces as before described.

While the clamping member proposed by this invention may take various more or less modified forms, it in all instances is 15 constructed and arranged to exercise true clamping functions. That is to say, this clamping member is positively and forcibly driven in a radial or spring-gripping direction by means of an appropriate co-operating element, so as variably to increase the 20 pressure on the spring-ends to create sufficient friction to prevent relative movement between the parts. In the forms shown by Figs. 10, 11, 12, 14, 15 and 16, the clamping member is U-shaped and has side flanges 25 that close the open-sides of the sockets with which they interfit, whereas in the other illustrated forms, it has the more elementary form of a simple bar.

30 Thus, as shown in Figs. 1, 2, 6, 7, 8 and 9 the clamping bar 13^a is a member having a central axial perforation 27 adapted to receive the shank of the bolt for the draw-up nut and having its ends 28 inclined in 35 parallelism with the end walls of the socket. Preferably when seated in its normal clamping relation, it snugly fits between the side walls of the socket, and its ends fall somewhat short of the end walls of the 40 socket so as to leave room for the clamped intervening spoke elements.

The clamping-member 13^b shown in Figs. 12 and 17 is for use with the sockets having the open sides and it provides side flanges 45 14 which normally close those open sides. Its inclined clamping ends 29 and 30 respectively co-operate with the inclined end-walls 18 and 26 of the respective socket-blocks, in the same relation as described in 50 the above paragraph. It is to be noted that the side flanges 14 of this invention in all forms of the clamping member fall short of any edge-abutment with any part of the rim, so that such member will have a 55 mounting permitting of radially outward adjustment or movement thereby enabling it to exercise clamping functions on the spring elements, as distinguished from an inert clip or clevis having but a single position and having its flanges in end-edge abutment with the felly or other part in such a way as to preclude a radially outward movement. Thus, the edge 31 of the flange 14 in Fig. 10 is spaced somewhat 60 65 away from the adjacent shoulder 32 on the

socket block 20 when the parts are normally assembled so as to enable a clamping movement to take place. So also, the edge 33 of the clamping member in Figs. 14 and 15 is normally interspaced from the 70 adjacent portion 34 of the felly. This is of great importance, as otherwise the part 13^b could not be brought into real clamping relations with the springs and the construction would be ineffective frictionally to 75 hold and bind the springs against relative movement.

The springs elements 3 enter the sockets aforesaid and extend along and in flat-wise contact with the inclined face of the end 80 walls thereof, and then they follow a bend at an obtuse angle and extend half-way across the bottoms of the sockets in the form of end flanges or feet 12. As shown by Figs. 8, 10, 14 and 18, the extreme end-edges are in edge-to-edge contact so as mutually to lock one another from twisting or like displacement movements.

To enable a leverage action to be exerted so as to force the clamping members against 90 the springs, bolts 35 or 36 extend radially from a head-mounting on a rim element and pass through an aperture in the bottom of the socket, through the matching half-apertures or recesses 37 in the edges of the 95 spring feet, and then they project through apertures 27 in the clamping member. Nuts 38 screw-threaded to the projecting portions of the bolts enable pressures to be 100 forcibly applied in a radially-outward direction to cause said clamping members to be adjustably urged into positive clamping relation with the springs 3. It may be noted that bolts 35 hold the socket blocks in place at the same time. 105

Having thus revealed my invention I claim as new and desire to secure by Letters Patent of the United States:—

1. A resilient wheel of the nature disclosed combining a hub, a series of flat metal 110 spokes arranged conversely in pairs to form two-part loop-like spokes radiating from said hub; an annulus of U-shaped channel iron forming the inner circumferential member of the rim; a tire; a ring-like member intervening circumferentially between and attached to both said tire and said annulus; said annulus providing an equi-spaced series of wide spoke-retaining sockets open toward said hub and having 115 their opposite end-walls sloping outwardly toward one another, each of said sockets being provided with a wide flat bottom surface extending in a circumferential direction for a distance greater than the depth 120 of said sockets; a forward spoke-element entering said socket and extending along the forward end-wall thereof and having a foot-like extension extending rearwardly along the bottom of said socket and terminating near 125 130

the transverse center-line thereof; a complementary rearward spoke-element also entering said socket and extending outwardly along the rearward end-wall thereof and also 5 having a foot-like extension extending forwardly along the bottom of said socket into edge-to-edge contact with the first mentioned foot-like extension; a retaining member interfitting in the crotch formed by said 10 spoke-elements, and means for restraining outward movement of said member.

2. A resilient wheel of the nature disclosed combining a hub, a series of flat metal spokes arranged conversely in pairs to form 15 two-part loop-like spokes radiating from said hub; an annulus of U-shaped channel iron forming the inner circumferential member of the rim; a tire; a ring-like member intervening circumferentially between 20 and attached to both said tire and said annulus; said annulus providing an equi-spaced series of wide spoke-retaining sockets open toward said hub and having their opposite end-walls sloping outwardly 25 toward one another, each of said sockets being provided with a wide flat bottom surface extending in a circumferential direction at an equal obtuse angle with both of said end-walls; a forward spoke-element 30 entering said socket and extending along the forward end-wall thereof and having a foot-like extension extending rearwardly along the bottom of said socket and terminating near the transverse center-line thereof; 35 a complementary rearward spoke-element also entering said socket and extending outwardly along the rearward end-wall thereof and also having a foot-like extension extending forwardly along the bottom of said 40 socket into edge-to-edge contact with the first-mentioned foot-like extension; a retaining member interfitting in the crotch formed by said spoke-elements, and means for restraining outward movement of said 45 member.

3. A vehicle wheel comprising a hub and a felly, flat metal spokes (3) arranged in pairs, the outer ends (12) of the spokes of each pair at the felly being bent to lie along 50 the felly and to fit against each other to lock the spokes against end movement or turning, means (11) for supporting said spokes in their outer sides at the bends, a clamping member for securing each pair of said inwardly bent ends to the felly fitting against the inner side of said spokes at the bends, and detachable means at the hub for rigidly securing each pair of spokes thereto.

4. A resilient wheel of the nature disclosed combining a hub, a series of flat metal spokes arranged conversely in pairs to form 60 two-part loop-like spokes radiating from said hub; an annulus of U-shaped channel iron forming the inner circumferential member of the rim; a tire; a ring-like

member intervening circumferentially between and attached to both said tire and said annulus; said annulus providing an equi-spaced series of wide spoke-retaining sockets open toward said hub and having their 70 opposite end-walls sloping outwardly toward one another, each of said sockets being provided with a transversely wide bottom surface; a spoke-element entering said socket and extending along the forward end-wall thereof and having a foot-like extension 75 extending along the bottom of said socket; a complementary spoke-element also entering said socket and extending outwardly along the rearward end-wall thereof 80 and also having a foot-like extension extending parallel with the bottom of said socket and contacting with the first-mentioned foot-like extension; a retaining member interfitting in the crotch formed by 85 said spoke-elements, and means for restraining outward movement of said member.

5. A vehicle wheel comprising a hub and a felly, flat metal spokes (3) arranged in outwardly bowed pairs, the outer ends (12) 90 of the spokes of each pair at the felly being bent at an obtuse angle to lie flat along the felly, the ends of the bent portions (12) of each pair fitting against each other, means (11) on said felly for supporting 95 said spokes on the outer sides extending inwardly toward the hub a short distance from the bend, a clamping member fitting flat against the bent ends and its ends bearing against the inner sides of said spokes 100 at the bends, whereby the spokes will be held against end movement or turning, and detachable means at the hub for rigidly securing each pair of spokes thereto.

6. A vehicle wheel comprising a hub and a felly, flat metal spokes arranged in pairs bowed apart in the plane of the wheel, the outer end portions of the spokes of each pair at the felly being bent at an obtuse angle to lie parallel with the felly, the end-edges of the bent portions of each pair being closely adjacent each other, a socket provided by said felly for receiving said spoke-ends and having its outer sides extending inwardly toward the hub a short distance 115 from the bend, a retaining member extending flatwise at the inner sides of the bent end-portions and having its elongated edges at the inner sides of said spokes at the bends, whereby the spokes will be confined 120 to said socket and held thereby against end movement or turning, and detachable means at the hub for securing each pair of spokes thereto.

7. A spring wheel of the class described comprising a hub, a felly, a felly plate positioned upon said felly and provided with a plurality of sockets formed therein having their end walls diverging toward the hub, sectional spokes secured to said hub and ter- 125 130

minating at the rim in feet-like flanges adapted to fit against the bottoms of said sockets, the spreading of said spokes being constrained by the diverging ends of said 5 sockets, a plate in said sockets and engaging the feet of said spokes, said plate being provided with angled ends adapted to cooperate with said sectional spokes, said plates being provided with parallel flanges, 10 said flanges projecting beyond the depth of said sockets, and means passing through said felly for holding said plates against accidental removal from said felly, the surface of said clamping plate facing said hub 15 being flush with the inner edges of said socket.

8. A spring wheel of the class described comprising a hub, a felly, a substantially U-shaped channel plate circumscribed by said felly, said plate provided with a plurality of spaced pockets indented therein, sectional spokes detachably carried by said hub and having their outer ends fitted in said pockets, retaining members for the outer ends of 20 said sectional spring spokes fitted in said pockets for securely holding the end of the spokes in engagement with said felly plate, and means for holding said retaining mem- 25

bers in said pockets and in engagement with said spokes and felly plate. 30

9. A vehicle wheel comprising a hub and a felly, flat metal spokes (3) arranged in pairs outwardly bowed from each other, the felly having separated sockets (11) on its inner face each for receiving the ends of 35 the pair of spokes, the end walls of said sockets extending across said felly and being at an angle to the flat bottom wall of said socket, the outer ends of the spokes converging as they enter said sockets with 40 their outer sides resting against said end walls and being bent (12) to lie along said felly in said sockets (11) and to fit against each other to lock the spokes against end movement or turning, and a clamping member 45 fitting between said converging ends within said sockets for holding said bent ends (12) and for supporting said pair of spokes on the inner side.

In testimony whereof I have hereunto set 50 my hand.

JOHN E. STRIETELMEIER.
